UNITED STATES PATENT OFFICE.

JOSEPH T. LEONARD, OF ST. CHARLES, MISSOURI.

EYEGLASS-CLEANER.

1,144,483.

Specification of Letters Patent. Patented June 29, 1915.

Application filed November 21, 1914. Serial No. 873,342.

To all whom it may concern:

Be it known that I, JOSEPH T. LEONARD, a citizen of the United States, residing at St. Charles, in the county of St. Charles and State of Missouri, have invented certain new and useful Improvements in Eyeglass-Cleaners, of which the following is a specification, reference being had to the accompanying drawings.

This invention relates to devices for cleaning the lenses of spectacles or eye-glasses and the primary object of the invention is to provide means for supporting two cleaning pads in such relation to each other that the lens of the eye-glass may be passed between the pads and the pads rubbed over the lens to cleanse the same, means being also provided whereby these pads are normally kept pressed against each other so as to prevent dust from collecting upon the surfaces of the pads, the pads when in use being sprung apart a sufficient distance to permit the insertion of a lens between them.

A further object of the invention is to provide means whereby the resilient arms supporting the pads may be readily turned into or out of a position between a supporting frame.

A further object of the invention is to provide means whereby the disks or webs of cleaning material may be readily applied to or removed from the device.

My invention is illustrated in the accompanying drawings wherein—

Figure 1 is a perspective view of my cleaning device with the arms separated to permit the replacement of the pads; Fig. 2 is a plan view showing the cleaning device closed; Fig. 3 is a side elevation of Fig. 2; Fig. 4 is a side elevation showing the cleaning pads in operative position; Fig. 5 is a plan view of one end of one of the arms; Fig. 6 is a fragmentary section showing the means for holding the arms in alinement; and Fig. 7 is an enlarged diametrical section of one of the cleaning pads.

Referring to these drawings, it will be seen that I provide a frame for supporting the eye-glass cleaner comprising a strip of metal which is bent upon itself to form two parallel legs designated 2. Each of these legs at a point adjacent to the closed end of the frame is transversely enlarged so as to form a disk 3, these disks being opposed to each other. At the forward end of the frame the legs are deflected toward each

other as at 4. Pivots mounted between the ends of the portions 4 of the legs are the arms 5. These arms at one end are deflected into contiguity with each other as at 6 and these deflected ends are inserted between the ends of the legs 2 and pivoted between these legs by means of a pivot screw 7. A spacing member 8 is disposed between the adjacent ends of the arms, this spacing member extending beyond the arms and being preferably formed to provide a small screw driver whereby the screws of spectacles or eye-glasses may be adjusted. The free ends of the arms 5 are enlarged to form the disks 9. The arms 5 are made of resilient material and deflected from each other so that the ends will normally have diverging relation. Each of the disks 9 carries upon it a ring 10 or annular wall, the diameter of this ring being slightly smaller than the diameter of the disk 9 so that a shoulder 11 is provided. A web 12 of chamois skin or like material suitable for cleaning eyeglasses is disposed over each ring 10 and is held in contact with the ring or annular wall by means of a removable ring 13 which is inserted over the annular wall and forced downward against the shoulder 11, straightening the web 12 of material tightly over the upstanding wall. If desired, a filling or stuffing of cotton designated 14 may be disposed within the cup formed by the annular wall 10, but this is not ordinarily necessary.

Preferably the portions 6 of the arms 5 are formed one with a stud 16 and the other with a perforation 15 and the resiliency of these arms 5 normally keep the stud projecting into the perforation so that the arms 5 move together. If it is desired however, to separate the arms 5 so that the webs 12 may be readily removed from the ends of the arms or replaced thereon, it is only necessary to force the arms apart so as to cause the disengagement of the stud with the perforation as in Fig. 1 and then replace the arms in parallel relation.

In the actual use of my invention, the lens is disposed between the cleaning pads or webs and the device is moved about so as to bring the cleaning pads in contact with every portion of the lens. When the device has been used, the arms 5 are forced toward each other and then rotated upon the pivot 7 so as to carry the arms into the space between the legs 2 so that the pads on the ends of the arms may be forced together,

bringing their surfaces into close contact and thus preventing dust from collecting upon the faces of the cleaning webs. Thus the cleaning pads are housed and protected 5 and the resilience of the arms 5 acts to hold the arms within the legs 2. The arms carrying the cleaning webs cannot readily or accidentally swing out of their position between the legs because of a frictional contact between the disks 9 and the disks 3.

10 The spacing member 8, it will be seen, is engaged with the arms 5 when these arms are forced toward each other by reason of the pin 16 passing through the perforation 15 in the end of the spacing member as well as through the perforation 15. Thus when the parts are in the position shown in Fig. 3, the spacing member 8 projects beyond the frame, and in order to shift the arms 5 outward from the frame and permit the use of the cleaning disks or pads the spacing member may be readily swung to project the arms. This spacing member 8 also forms a small screw driver for eye glasses.

15 It will be noted that the construction above described has a number of advantages. First, I provide a protecting frame or case within which the cleaning members are normally housed. Second, I provide means for 20 keeping the wiping surfaces in contact with each other and thus free from dust. Third, when the wiping surfaces are turned out of contact with the frame they immediately spring apart to an extent permitting the insertion of an eye-glass lens, and fourth, I provide a very ready means whereby the wiping webs may be changed when it becomes necessary to do so. Still another advantage resides in the fact that though the 25 arms carrying the wiping members are normally disposed opposite each other, yet when necessary it is possible to shift the arms into diverging relation, thus permitting the ready removal of the wiping webs.

30 Having described my invention, what I claim is:

1. An eye-glass cleaner including a frame having oppositely disposed parallel members, divergently resilient arms pivoted 35 within the frame and between said members, lens cleaning pads carried by the arms, the space between the said members of the frame being less than the combined thickness of

the cleaning pads and adjacent portions of the arms when the pads are compressed 55 whereby when the arms and pads are turned into position within the frame said pads shall be held in close contact with each other, said arms being yieldingly separated by their resilience when turned to project 60 from the frame.

2. An eye-glass cleaner comprising a substantially U-shaped frame having parallel legs, the outer ends of the legs being deflected toward each other, a pair of divergent spring arms disposed between the legs and having their inner ends deflected toward each other, the inner ends of the arms being pivoted to the inner ends of the legs and the free ends of the arms being thereby 65 adapted to be disposed between the legs of the frame or out of such position, and cleaning pads carried upon said arms, the space between the legs being less than the combined thickness of the cleaning pads and 70 adjacent portions of the arms when the pads are compressed whereby to cause the pads to be held in contact with each other when the pads are disposed between the arms.

3. An eye-glass cleaner comprising a substantially U-shaped frame, the free ends of the legs of said frame being deflected toward each other, a pair of divergent spring arms having their ends disposed between the deflected ends of the legs, a spacing member 75 disposed between said arms and extending beyond the adjacent end of the frame, a pin passing through the free ends of the legs, through said arms and the spacing member to constitute a pivot for the arms 80 and spacing member, and means for holding the arms and spacing member in parallel relation to each other when the arms are pressed toward each other and against the spacing member, but permitting the arms 85 to be turned each independently upon the pivot pin and therefore into rotatably separated relation when sprung apart and away 90 from the spacing member.

In testimony whereof I hereunto affix my 100 signature in the presence of two witnesses.

JOSEPH T. LEONARD.
